UNITED STATES PATENT OFFICE

103,189

DESIGN FOR A DRY CELL REACTIVATOR HOUSING

Joseph H. Staley, Columbus, Ind., assignor to
Stirney Electric Corporation, Columbus, Ind.

Application August 8, 1936, Serial No. 64,295

Term of patent 14 years

To all whom it may concern:

Be it known that Joseph H. Staley, a citizen of the United States, residing at Columbus, in the county of Bartholomew and State of Indiana, has invented a new, original, and ornamental Design for a Dry Cell Reactivator Housing, of which the following is a specification, reference being had to the accompanying drawing, forming part thereof.

Fig. 1 is a top plan view of a dry cell reactivator housing showing my new design;

Fig. 2, a side elevation;
Fig. 3, a front elevation; and
Fig. 4, a rear elevation.

I claim:

The ornamental design for a dry cell reactivator housing, as shown.

JOSEPH H. STALEY.
